 11 Claims. (Cl. 260—524)

This application is a continuation-in-part of our application for United States Letters Patent, Serial No. 19,500, filed April 4, 1960, now abandoned.

This invention relates to the manufacture of aromatic carboxylic acids. It is more particularly concerned with a process for oxidizing a methyl-substituted aromatic compound to the corresponding carboxylic acid or acids.

As is well known to those skilled in the art, it has been proposed to oxidize aromatic compounds, particularly alkyl-substituted aromatic hydrocarbons, to produce aromatic carboxylic acids. The alkylaromatic hydrocarbons having two or more carbon atoms in the alkyl group have been oxidized with relative ease. The oxidation of methyl-substituted aromatic hydrocarbons, on the other hand, has been relatively difficult. Even with catalysts, temperatures of the order of 150—225° C. and higher have been required, for example, to oxidize xylene to toluic acid. In order to maintain a liquid phase, superatmospheric pressures were necessary.

It has now been found that methyl-substituted aromatic compounds (methylaromatics) can be oxidized in the liquid phase at atmospheric pressure. It has been discovered that certain branched-chain alkyl-substituted aromatic hydrocarbons act as promoters for the oxidation of methylaromatic compounds to aromatic carboxylic acids at atmospheric pressure. Accordingly, it is a broad object of this invention to provide a process for producing aromatic carboxylic acids. Another object is to provide a method for oxidizing methylaromatic compounds to carboxylic acids. A specific object is to provide a process for oxidizing methylaromatic compounds to aromatic carboxylic acids at atmospheric pressure. Another specific object is to provide a process for oxidizing methylaromatic compounds to aromatic carboxylic acids that is promoted by certain branched-chain alkyl-substituted aromatic hydrocarbons.

In general, the present invention provides a method for producing aromatic carboxylic acids that comprises establishing a reaction mixture of a methylaromatic compound and an alkylaromatic hydrocarbon promoter, wherein the alkyl group has a secondary carbon atom directly attached to the aromatic nucleus, and the weight ratio of said methylaromatic compound to said alkylaromatic promoter being between about 0.1:1 and about 10:1, maintaining said reaction mixture at a temperature varying between about 50° C. and the boiling point of said methylaromatic compound; contacting said reaction mixture with oxygen-containing gas, with or without an oxidation catalyst, at a flow rate varying between about 0.1 cubic foot per hour and about 4 cubic feet per hour, for a period of time varying between about 0.5 hour and about 10 hours; and recovering from the reaction mixture an aromatic carboxylic acid.

The process of this invention is applicable to the oxidation of methyl-substituted aromatic hydrocarbons to the corresponding aromatic carboxylic acids at temperatures sufficiently low to permit liquid phase operation at atmospheric pressure. Examples of the type of oxidation contemplated herein include the oxidation of toluene to benzoic acid, the oxidation of xylene to toluic acid, and the oxidation of methylnaphthalene to naphthoic acid. It

2

has also been found that methyl-substituted aromatic carboxylic acids can be directly oxidized to polycarboxylic aromatic acids, without resort to converting the methylaromatic carboxylic acid to the ester. Thus, for example, it is contemplated to oxidize p-tolanic acid to terephthalic acid, without first converting to the methyl toluate ester. Accordingly, non-limiting examples of the methyl-substituted aromatic compounds oxidizable in the process of this invention include, toluene, o-xylene, m-xylene, p-xylene, hemimellitene, pseudocumene, mesitylene, α -methylnaphthalene, β - methylnaphthalene, dimethylnaphthalene, o-tolanic acid, m-tolanic acid, p-tolanic acid, hemimellitic acid, xylic acid, mesitylenic acid, methylpyridine, p-chlorotoluene, tolunitrile.

It is a discovery of this invention that the aforementioned methylaromatic compounds, which are difficult to oxidize at atmospheric pressure, are readily oxidized when a promoter is used. The promoters contemplated herein are alkylaromatic hydrocarbons in which the alkyl group has a secondary carbon atom directly attached to the aromatic nucleus. These compounds have a structure:

wherein R and R' are alkyl groups containing 1-3 carbon atoms. These compounds have one hydrogen atom in a position alpha to the aromatic nucleus. Non-limiting examples of promoters include cumene, isobutylbenzene, isoamylbenzene, 3-phenylpentane, 3-phenylhexane, and 4-phenylheptane. Cumene is particularly preferred from the standpoint of its ready availability and effectiveness.

The amount of promoter used, in proportion to the amount of methylaromatic charge, can vary somewhat. Generally, the weight ratio of methylaromatic compound to promoter will vary between about 10:1 and about 0.1:1. Preferably, it will be between about 4:1 and about 0.2:1.

The oxidation reaction is carried out in the liquid phase by contacting the methylaromatic-promoter mixture with oxygen in the presence of a catalyst, at temperatures which permit operation at atmospheric pressure. In the absence of the promoter, the oxidation reaction (as previously had been proposed) requires elevated temperatures which are considerably higher than the boiling point of the methylaromatic compound. Accordingly, superatmospheric pressures have been required to maintain liquid phase. The present process operates at temperatures ranging from about 50° C. up to the boiling point of the methylaromatic compound reactant. For example, toluene (B.P.=110.8° C.) can be oxidized readily, by the process of this invention, at about 110° C. Xylenes (B.P.=138-140° C.) are processed readily at about 135° C. In general practice under the present invention, the highest reaction temperature will be within about 1-5° C. of the boiling point of the methylaromatic compound reactant.

Oxygen is supplied to the process as relatively pure oxygen or in the form of a molecular oxygen-containing gas, such as air. The amount of oxygen used (measured in terms of molecular oxygen, in the case of oxygen-containing gas) will vary between about 0.1 cubic foot per hour and about 4 cubic feet per hour, and preferably between about 0.2 cubic foot per hour and about 0.5 cubic foot per hour. The time of reaction will depend upon the oxygen flow rate and the temperature used. In general, the reaction time will vary between about 0.5 hour and about 10 hours, preferably between about one hour and about 5 hours.

The use of the aforescribed alkylaromatic hydro-

carbon promoter, such as cumene, to promote the oxidation of methylaromatic hydrocarbons has a general application. Thus, the promotion effect has been noted even in the absence of an oxidation catalyst. The effect, however, is less pronounced, i.e. relatively lower conversions to carboxylic acids are noted for the same reaction conditions. In general, therefore, the alkylaromatic hydrocarbon promoter will effect improved yields in any liquid phase, catalytic process for oxidizing methylaromatic hydrocarbons to aromatic carboxylic acids. In its broadest aspect, the promotional effect of this invention is not dependent upon the particular oxidation catalyst selected and will be observed with any of the oxidation catalysts known to the art.

Various types of oxidation catalysts used in the art have been extensively investigated and found effective in this invention. One preferred type is a heavy metal phthalocyanine or porphorazine, such as, for example, iron phthalocyanine. Another type of catalyst includes metal salts of organic carboxylic acids, such as, cobalt naphthenate, cobalt permanganate, cerium chloride, copper phosphate, vanadium chloride, and manganese acetate. The more effective catalysts of this type are those wherein the metal is in its lower valence state, e.g. cobaltous naphthenate or acetate. Generally speaking, the oxidation catalysts commonly used include the solid polyvalent metals having an atomic weight between about 50 and 200. The metals, themselves, may be used in the finely divided metallic state, or as oxides or as compounds of the types already referred to. Mixtures of two or more oxidation catalysts may be utilized if desirable.

In the process of this invention, part of the alkylaromatic promoter will be oxidized. In the case of cumene, some will be converted to acetophenone, a material useful as a perfume ingredient and as lacquer thinner. The main products, aromatic carboxylic acids, can be removed in any of the various ways for separating organic acids from hydrocarbons. Thus, the carboxylic acid can be neutralized by adding an aqueous solution of alkali, such as aqueous sodium or potassium hydroxide, to the reaction product to obtain an aqueous solution of the salt of the aromatic carboxylic acid. The aqueous solution is separated from the organic material (unreacted reactant, ketones, etc.) and then acidified to release the aromatic

amples, or by the operations or manipulations involved. As will be apparent to those skilled in the art, other reactants and conditions, as set forth herein, can be used to practice this invention.

OXIDATION OF TOLUENE

Example 1

A mixture of 80 grams toluene, 20 grams cumene (promoter), and 0.5 gram cobalt naphthenate (catalyst-4.5% Co) was heated at 110° C. in a reaction vessel equipped with a reflux condenser attached to a small water take-off device to azeotropically remove water from the reactants as it was formed. Oxygen was bubbled through the heated reaction mixture at the rate of 0.5 cubic foot per hour, for three hours. The reaction mixture was cooled and extracted with 50 ml. of 10% aqueous solution of sodium hydroxide. The caustic extract was neutralized with 10% hydrochloric acid and the solid acid that separated was removed by filtration. The crude acid (31 grams) was recrystallized from hot water to yield a product melting at 119-121° C. (Reported for benzoic acid=121° C.). The acid number was 459 (theory for benzoic acid=460). The caustic-insoluble oil fraction was analyzed by vapor phase chromatographic analysis and showed 8% acetophenone, i.e. conversion of about 40% of the cumene to acetophenone. Unreacted toluene and cumene are recoverable by distillation for recycle to the process.

Example 2

Another run similar to that of Example 1 was made, except that no cumene promoter was used. After 3½ hours operation at 110° C. using an oxygen flow rate of 0.5-0.6 cubic foot per hour, there was produced no benzoic acid.

Examples 3 and 4

Two runs were made, as described in Example 1, using air as the source of oxygen. The flow rates were 0.7-0.8 cubic foot of air per hour, equivalent to an oxygen flow rate of about 0.14-0.16 cubic foot per hour. In one run the ratio of toluene to cumene was 4:1 and in the other, 1:1. Pertinent data on these runs and on the runs of Examples 1 and 2 are summarized in Table I.

TABLE I

Examples	Reactants	Time, Hrs.	Temp., °C.	Wt. percent Conv. Toluene to Benzoic Acid	Wt. percent Conv. Cumene to Acetophenone

carboxylic acid products. In many cases, however, the aromatic carboxylic acid product will crystallize out of the reaction mixture when it is cooled. In this case, the product can be removed by filtration, without resort to neutralization. In other cases, the product can be separated by distillation methods, usually under reduced pressure.

The following specific working examples are for the purpose of demonstrating the operation of the process of this invention and the superiority thereof. It must be strictly understood that the present invention is not to be limited by the reactants and conditions used in the ex-

OXIDATION OF XYLENE

Example 5

In a reaction vessel provided with reflux condenser and water take-off trap, were placed 50 grams p-xylene, 50 grams cumene (promoter), and 0.5 gram iron phthalocyanine (catalyst). This reaction mixture was maintained at about 135° C. by externally heating the reaction vessel with refluxing xylene. Oxygen was bubbled through the heated reaction mixture at a rate of 0.3-0.4 cubic foot per hour for 2 hours. The reaction mixture was then cooled in an ice bath, whereupon crystals sepa-

rated. These were removed by filtration, yielding a crude product weighing 17 grams. This product was recrystallized from an alcohol-water mixture to yield clean white crystals melting at 176-9° C. (p-toluic acid melts at 179° C.). The white crystalline product when mixed with known p-toluic acid ("mixed" melting point) did not depress the melting point (179° C.) of the known p-toluic acid.

The white crystalline product was further identified as p-toluic acid by treating 0.2 gram with 5 ml. thionyl chloride under reflux for 15 minutes and then pouring the mixture into cold concentrated ammonium hydroxide. The precipitated amide was dried and found to melt at 160-3° C. (p-toluamide melts at 165° C.).

The oil recovered after filtration of the crude acid product was analyzed by vapor phase chromatography and found to contain 50.8% cumene and p-xylene and 25.9% acetophenone. The remaining material contained dicumyl and small amounts of higher molecular weight products. The cumene and p-xylene unreacted can be recycled to the process. The run is summarized in Table II.

Example 6

A run similar to that of Example 5 was made, except that no cumene was used. The charge was 75 grams p-xylene and 0.375 gram iron phthalocyanine. Oxygen was bubbled through the charge at 135° C. for 5 hours, at a rate of 0.3 cubic foot per hour. There was no measurable yield of oxidation product. The run is summarized in Table II.

Example 7

Using the reaction system described in Example 5, a charge of 60 grams o-xylene, 60 grams cumene, and 0.6 gram iron phthalocyanine was heated at 135° C. Oxygen was bubbled through the charge at a rate of 0.3-0.4 cubic foot per hour for 3 hours. The product was cooled and extracted with 200 ml. of 10% potassium hydroxide. The aqueous caustic extract was separated

and poured carefully into cold, concentrated ammonium hydroxide and the precipitated amide was separated and recrystallized from water. The dried amide melted at 145-6° C. Reported melting point of orthotoluamide is 147° C.

The oil remaining after caustic extraction weighed 84 grams. It was examined by vapor phase chromatography and found to contain 76.1% cumene and o-xylene, 19.6% acetophenone, and small amounts of dimeric products. The run is summarized in Table II.

Example 8

A run similar to that of Example 7 was made, except that no cumene was used. The charge was 80 grams o-xylene and 0.4 gram iron phthalocyanine. Oxygen was bubbled through the charge at 135° C. for 3 hours, at a rate of 0.3 cubic foot per hour. There was no measurable yield of oxidation product. The run is summarized in Table II.

Example 9

Using the reaction system and technique of the run of Example 7, a charge of 50 grams m-xylene, 50 grams cumene, and 0.5 gram iron phthalocyanine was oxidized for 3.2 hours at 135° C., using an oxygen rate of 0.3-0.4 cubic foot per hour. A crude acid product was obtained (14 grams) which, when recrystallized from water, melted at 107-9° C. Reported melting point of metatoluic acid is 110° C.

The oil recovered after caustic extraction weighed 84 grams. Vapor phase chromatography established it as 70.0% m-xylene and cumene, 18.9% acetophenone, and minor amounts of dimeric products. The run is summarized in Table II.

Example 10

A run was made as described in Example 9, except that no cumene promoter was used. The charge of 100 grams m-xylene and 0.5 gram iron phthalocyanine was oxidized for 24 hours at 135° C., using an oxygen rate of 0.3 cubic foot per hour. No measurable yield of oxidation product was obtained. The run is summarized in Table II.

TABLE II

Examples	Reactants	Reaction Conditions			Solid Acids, Wt. Percent	Percent Conv. Xylene to Acid	Percent Aceto- phenone
		O ₂ Input, cu. ft./hr.	Temp., °C.	Time, Hrs.			
5.....	[p-Xylene, 50 g. Cumene, 50 g. [Fe PTC, ¹ 0.5 g.]	0.3-0.4	135	2	17	34	26
6.....	[p-Xylene, 75 g. [Fe PTC, 0.375 g. [o-Xylene, 60 g.	0.3	135	5	Nil	Nil	-----
7.....	[Cumene, 60 g. [Fe PTC, 0.6 g. [o-Xylene, 80 g.	0.3-0.4	135	3	12	24	20

¹ Fe PTC is iron phthalocyanine.

and acidified with 10% hydrochloric acid. Upon cooling, yellow crystals formed and these were separated by filtration. The crude crystals weighed 12 grams and melted at 55-75° C. They were decolorized with activated charcoal and recrystallized from alcohol-water solution. The purified crystals melted at 102-3° C. (M.P. of orthotoluic acid=103.4° C.). A mixed melting point with the product of this example and known orthotoluic acid showed no depression of the melting point.

The product was further characterized as orthotoluic acid by treating 0.5 gram with 5 ml. thionyl chloride under reflux for 30 minutes. The reaction mixture was

65 From the data in Table II it will be appreciated that good yields of toluidic acids are obtained by the process of this invention, using liquid phase operation at atmospheric pressure. The acetophenone produced is a utilizable by-product. Unreacted xylene and cumene can be recycled to extinction.

OXIDATION OF OTHER METHYLAROMATIC COMPOUNDS

Example 11

Mesitylene (60 grams), cumene (60 grams) and iron phthalocyanine (0.6 gram) were heated at 135° C. for 5½ hours while oxygen was bubbled through the solution.

The cooled oxidation product was extracted with three 100 ml. portions of 10% sodium hydroxide solution, leaving 90 grams of caustic-insoluble oil. Neutralization of the caustic extract with 10% hydrochloric acid produced 25 grams of crude acid, which was crystallized from water to yield white crystals having a melting range of 157-160° C. The reported melting point of mesitylenic acid is 166° C. The acid number of the acid was 368 (theory for mesitylenic acid, 374).

Example 12

A solution containing 20 grams of p-toluic acid, 80 grams of cumene and 0.5 gram of iron phthalocyanine were heated at 135° C. while oxygen was passed through the solution at a rate of 0.4 cubic foot per hour for 3 hours. The solution was filtered hot and 2.35 grams of solid acid were separated in this fashion (terephthalic acid is extremely insoluble in most organic solvents while p-toluic acid is soluble in hot organic solvents). The solid was digested with two 400 ml. portions of hot water and the insoluble solid separated by filtration and dried in a drying pistol, weight 2.32 grams. This solid did not melt when heated to 220° C. and gave an acid number with two breaks (indicative of two carboxyl groups). Acid numbers found: 337, 453; theoretical for terephthalic acid: 338, 674. (Solubility problems render it difficult to obtain a satisfactory "second" break in the acid number determination for pure terephthalic acid.)

Example 13

Sixty grams of p-xylene and 60 grams of cumene were oxidized (note: no oxidation catalyst was used) at 135° C. for 7 hours using oxygen at a flow rate of 0.3 cubic foot per hour. The crude p-toluic acid obtained weighed 6 grams and was similar to that prepared in Example 5. Recrystallization gave a solid p-toluic acid of melting point 174-8° C. which did not depress the melting point of known p-toluic acid when added thereto.

Although the present invention has been described with preferred embodiments, it is to be understood that modifications and variations may be resorted to, without departing from the spirit and scope of this invention, as those skilled in the art will readily understand. Such variations and modifications are considered to be within the purview and scope of the appended claims.

What is claimed is:

1. A method for producing aromatic carboxylic acids that consists essentially of establishing a reaction mixture of a methylaromatic hydrocarbon and an alkylaromatic hydrocarbon promoter having the structure:

wherein R and R' are alkyl groups having 1-3 atoms, and the weight ratio of said methylaromatic hydrocarbon and said alkylaromatic promoter being between about 0.1:1 and about 10:1; maintaining said reaction mixture at a temperature varying between about 50° C. and about 135° C. and under atmospheric pressure; and contacting said reaction mixture in the liquid phase with a molecular oxygen-containing gas at a flow rate, measured in terms of oxygen, varying between about 0.1 cubic foot per hour and about 4 cubic feet per hour per 100 g. of said reaction mixture, and for a period of time varying between about 0.5 hour and about 10 hours.

2. The process defined in claim 1, wherein said process is carried out in the presence of a heavy metal oxidation catalyst.

3. A method for producing benzoic acid that consists essentially of establishing a reaction mixture of toluene

and an alkylaromatic hydrocarbon promoter having the structure:

wherein R and R' are alkyl groups having 1-3 C atoms, and the weight ratio of said toluene to said alkylaromatic promoter being between about 0.2:1 and about 4:1; maintaining said reaction mixture at a temperature varying between about 50° C. and about 110° C.; and under atmospheric pressure and contacting said reaction mixture with a molecular oxygen-containing gas at a flow rate, measured in terms of oxygen, varying between about 0.2 cubic foot per hour and about 0.5 cubic foot per hour per 100 g. of said reaction mixture, in the presence of cobalt naphthenate catalyst, and for a period of time varying between about one hour and about 5 hours.

20 4. A method for producing benzoic acid that consists essentially of establishing a reaction mixture of toluene and cumene promoter, the weight ratio of said toluene to said cumene being between about 0.2:1 and about 4:1; maintaining said reaction mixture at a temperature of about 110° C. and under atmospheric pressure; contacting said reaction mixture with oxygen at a flow rate varying between about 0.2 cubic foot per hour and about 0.5 cubic foot per hour per 100 g. of said reaction mixture, in the presence of cobalt naphthenate catalyst, and for a period of time varying between about one hour and about 5 hours; and recovering benzoic acid from the reaction mixture.

30 5. A method for producing benzoic acid that consists essentially of establishing a reaction mixture of toluene and cumene promoter, the weight ratio of said toluene to said cumene being between about 0.2:1 and about 4:1; maintaining said reaction mixture at a temperature of about 110° C. and under atmospheric pressure; contacting said reaction mixture with air at a flow rate, measured in terms of oxygen, varying between about 0.2 cubic foot per hour and about 0.5 cubic foot per hour per 100 g. of said reaction mixture, in the presence of cobalt naphthenate catalyst, and for a period of time varying between about one hour and about 5 hours; and recovering benzoic acid from the reaction mixture.

40 6. A method for producing toluic acids that consists essentially of establishing a reaction mixture of xylene and cumene promoter, the weight ratio of said xylene to said cumene being between about 0.2:1 and about 4:1; maintaining said reaction mixture at a temperature varying between about 50° C. and about 135° C. and under atmospheric pressure; and contacting said reaction mixture with oxygen at a flow rate varying between about 0.2 cubic foot per hour and about 0.5 cubic foot per hour per 100 g. of said reaction mixture, and for a period of time varying between about 0.5 hour and about 5 hours.

50 7. A method for producing paratoluic acid that consists essentially of establishing a reaction mixture of p-xylene and cumene promoter, the weight ratio of said p-xylene to said cumene being between about 0.2:1 and about 4:1; maintaining said reaction mixture at a temperature of about 135° C. and under atmospheric pressure; contacting said reaction mixture with oxygen at a flow rate varying between about 0.2 cubic foot per hour and about 0.5 cubic foot per hour per 100 g. of said reaction mixture in the presence of iron phthalocyanine catalyst, and for a period of time varying between about one hour and about 5 hours; and recovering paratoluic acid from the reaction mixture.

60 8. A method for producing orthotoluic acid that consists essentially of establishing a reaction mixture of o-xylene and cumene promoter, the weight ratio of said o-xylene to said cumene being between about 0.2:1 and about 4:1; maintaining said reaction mixture at a temperature of about 135° C. and under atmospheric pres-

sure; contacting said reaction mixture with oxygen at a flow rate varying between about 0.2 cubic foot per hour and about 0.5 cubic foot per hour per 100 g. of said reaction mixture, in the presence of iron phthalocyanine catalyst, and for a period of time varying between about one hour and about 5 hours; and recovering orthotoluic acid from the reaction mixture.

9. A method for producing metatoluic acid that consists essentially of establishing a reaction mixture of m-xylene and cumene promoter the weight ratio of said m-xylene to said cumene being between about 0.2:1 and about 4:1; maintaining said reaction mixture at a temperature of about 135° C. and under atmospheric pressure; contacting said reaction mixture with oxygen at a flow rate varying between about 0.2 cubic foot per hour and about 0.5 cubic foot per hour per 100 g. of said reaction mixture, in the presence of iron phthalocyanine catalyst, and for a period of time varying between about one hour and about 5 hours; and recovering metatoluic acid from the reaction mixture.

10. A method for producing mesitylenic acid that consists essentially of establishing a reaction mixture of mesitylene and cumene promoter, the weight ratio of said mesitylene to said cumene being between about 0.2:1 and about 4:1; maintaining said reaction mixture at a 25 temperature of about 135° C. and under atmospheric pressure; contacting said reaction mixture with oxygen at a flow rate varying between about 0.2 cubic foot per hour and about 0.5 cubic foot per hour per 100 g. of said reaction mixture, in the presence of iron phthalocyanine 30 catalyst, and for a period of time varying between about

one hour and about 5 hours; and recovering mesitylenic acid from the reaction mixture.

11. A method for producing terephthalic acid that consists essentially of establishing a reaction mixture of p-toluic acid and cumene promoter, the weight ratio of said p-toluic acid to said cumene being between about 0.2:1 and about 4:1; maintaining said reaction mixture at a temperature of about 135° C. and under atmospheric pressure; contacting said reaction mixture with oxygen at a flow rate varying between about 0.2 cubic foot per hour and about 0.5 cubic foot per hour per 100 g. of said reaction mixture, in the presence of iron phthalocyanine catalyst, and for a period of time varying between about one hour and about 5 hours; and recovering terephthalic acid from the reaction mixture.
